UNITED STATES PATENT OFFICE

ABEL BURMAN, OF SAN GABRIEL, CALIFORNIA

POCKET PENHOLDER

Application filed May 24, 1929. Serial No. 365,654.

This invention relates to pocket-pen-holders.

The general object of the invention is to provide an improved case which is adapted to fit a pocket in a garment, to maintain pens and pencils in the pocket and in their correct alignment.

A further object of the invention is to provide a pocket-pen-holder comprising an impervious case, having spaced side walls and having a brush secured within the case to hold pens and pencils properly spaced and in alignment.

Other objects of the invention will be apparent from the following description taken in connection with the accompanying drawings, wherein:

Fig. 1 is a side elevation partly in section showing my improved pocket-pen-holder.

Fig. 2 is an end elevation partly in section showing the pen holder.

Fig. 3 is a top plan view of the pen holder, and

Fig. 4 is a longitudinal sectional view taken on line 4—4, Fig. 1.

In the accompanying drawings I have indicated my pocket pen holder as embodied in a case 10. This case may be made of celluloid, rubber, fiber, leather, metal or suitable composition, and as shown the case includes a front 11, and a back 12. The front and back are joined by curved ends 13 and the lower end of the case is closed by a bottom 14.

The bottom of the case has a loop 15 thereon. The loop includes aperture 16 through which suitable fastening means may be inserted in securing the case in a pocket.

Within the case I arrange a brush, indicated generally at 17. This brush includes a back 18, and spaced, tufted bristles 19. The brush may be made of bristles, of rubber or of wire, and they extend a sufficient distance to engage the pens or pencils to thus keep the articles from sliding out of the pocket or from becoming disarranged.

From the foregoing description it will be apparent that I have provided an improved pocket-pen-holder which can be eco-

nomically manufactured and which is highly efficient in use.

Having thus described my invention, I claim:

A pocket-pen-holder comprising an impervious case having spaced side walls thereon and having a bottom and an open top, a brush including a back having bristles thereon, the back of said brush being rigidly secured to one of the inner walls of said case adjacent the open end thereof, said bristles firmly embedded in the back of said brush and being flexible and being shorter than the distance between said side walls, said bristles comprising spaced tufts, certain of said bristles being adapted to urge a pen towards the side wall remote from said brush and other of said bristles being adapted to hold a pen against lateral movement.

In testimony whereof, I hereunto affix my signature.

ABEL BURMAN.
